US00D985543S

(12) **United States Design Patent** (10) **Patent No.:** **US D985,543 S**
Wei et al. (45) **Date of Patent:** **** May 9, 2023**

(54) **BRACKET**

(71) Applicant: **Anker Innovations Technology Co., Ltd.**, Changsha (CN)

(72) Inventors: **Jingxuan Wei**, Shenzhen (CN); **Zheng Wei**, Shenzhen (CN)

(73) Assignee: **Anker Innovations Technology Co., Ltd.**, Changsha (CN)

(**) Term: **15 Years**

(21) Appl. No.: **29/785,648**

(22) Filed: **May 26, 2021**

(51) LOC (14) Cl. **14-01**

(52) U.S. Cl.

USPC **D14/224**; D8/354

(58) **Field of Classification Search**

USPC D8/354, 358, 363, 366, 373, 375, 379, D8/382, 400-402, 404, 499, 46, 300, D8/321-322, 383-384, 387, 397, 399, D8/356, 364-365, 374, 376-377, D8/380-381; D11/89, 132, 93, 79, 80; D12/223, 414, 400, 406; D25/61, 102, D25/119-122, 133, 138, 140, 164, 199; D14/223-224.1

CPC H04R 1/026; H04R 1/02

(57) **CLAIM**

The ornamental design for a bracket, as shown and described.

DESCRIPTION

FIG. 1 is a front top perspective view of a bracket showing our new design;

FIG. 2 is a rear bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is an enlarged view of the encircled portion 9 indicated in FIG. 7.

The broken lines depict portions of the bracket that form no part of the claimed design. The dot-dash broken lines depict the boundaries of the enlarged detail view and form no part of the claimed design.

1 Claim, 9 Drawing Sheets
